UNITED STATES PATENT OFFICE.

DANA K. ALDEN, OF BOSTON, MASSACHUSETTS.

DESIGN FOR A CASTER.

SPECIFICATION forming part of Design No. 20,134, dated September 9, 1890.

Application filed July 31, 1890. Serial No. 360,587. Term of patent 3½ years.

To all whom it may concern:

Be it known that I, DANA K. ALDEN, a citizen of the United States, residing at Boston, in the county of Suffolk and State of Massachusetts, have invented and produced a new and original Design for Casters; and I do declare the following to be a full, clear, and exact description of the same.

The leading feature of my design consists in a flat legless base A, from which rises the post or standard B, having a loop or ring b at its upper end, as shown in the drawing. Above the flat legless base A is arranged upon

the post B the rings C C, as shown in the accompanying drawing.

What I claim is—

The design for a caster herein shown and described, the same comprising the flat legless base A, the post B thereon, and the rings C C on said post, as set forth.

In testimony whereof I affix my signature in presence of two witnesses.

DANA K. ALDEN.
